UNITED STATES PATENT OFFICE.

SAMUEL BODINGER, OF NEW YORK, N. Y.

EASEL-FRAME.

No. 838,516.

Specification of Letters Patent.

Patented Dec. 18, 1906.

Application filed February 2, 1906. Serial No. 299,086.

To all whom it may concern:

Be it known that I, SAMUEL BODINGER, a subject of the Emperor of Austria-Hungary, and a resident of New York, borough of Manhattan, in the county of New York and State of New York, have made and invented certain new and useful Improvements in Easel-Frames, of which the following is a specification.

10 My invention relates to an improvement in easel-frames, and more particularly to the support therefor, the object being to provide an article of this kind or character whereby the support is adjustably held in its several 15 positions, which may be folded tightly against the frame in order that the same may be packed in a small compass for transportation, and which support when in its folded adjustment may be used or employed 20 as a handle whereby to conveniently carry the frame with its attached article.

A further object of my invention is to produce an article of this kind which shall be cheap to manufacture and simple and economical in its construction; and with these 25 and other ends in view it consists in certain novel features of construction and combinations of parts, as will be hereinafter fully described, and pointed out in the claims.

30 In the accompanying drawings, Figure 1 is a view in front elevation of a frame having my invention applied thereto. Fig. 2 is a rear view of the same, showing the support in its folded adjustment and in position to be 35 employed as a handle. Fig. 3 is a view in perspective of the frame, the support being in its lowered adjustment. Fig. 4 is a detached view of one of the retaining-plates, showing a part of the support in its raised 40 or folded adjustment. Fig. 5 is a similar view, showing a part of the support in its lowered adjustment. Fig. 6 is a sectional view taken on the line 6 6 of Fig. 2.

Referring to the drawings, A represents a 45 frame formed of wood, metal, or other desired material and of any suitable size or pattern and may, if required, be provided with an opening B, wherein to set a mirror or other article, (not shown,) the frame being 50 such as may be adapted to support a picture, album, or other article. To the back of the frame A are secured, at each side thereof, the retaining-plates C, each of which is preferably formed from a single piece of sheet 55 metal and bent or folded into the shape as

shown—that is, with the part or portion a, by means of which it is nailed, screwed, or otherwise fastened to the frame A and with the part or portion b bent or folded at right angles to the plate a, that portion of the 60 metal joining the plates a b and forming the angle or bend being so curved as to form the recess c, of such size as to nicely contain between the metal and the frame A one arm or rod of the support, as hereinafter described. 65 The plate b is also formed with the recess d by curving or stamping the metal of the plate inwardly, this recess or groove being such as to nicely contain the arm or bar of said support when the latter is lowered. In 70 the plate a is also formed a channel or recess by stamping or curving the metal outwardly, as illustrated at e, said recess extending transversely across the plate and adapted to contain the bent ends f of the support, the 75 latter being preferably made from a bar or single piece of wire bent to form arms D, with the connecting-arm E. In this channel or recess e rest the bent ends f and held therein between the metal of said channel and the 80 frame A, said bent ends f being upset or headed, as at g, in order to prevent their disengagement from the retaining-plates.

When the easel-frame is in use, the support is lowered to the position as illustrated 85 in Fig. 3—that is, the bars D rest in the channels or recesses d, formed in the plates b and held therein by the spring or tension of the wire of which the support is formed. When it is desired to pack the article for transporta- 90 tion, the bars D of the support are slightly sprung outwardly, as illustrated by dotted lines in Fig. 2, whereupon they may be turned out of the recesses or channels d and the support folded up against the frame into 95 the position as illustrated in Figs. 1, 2, and 4, the said bars D springing into place in the channels or recesses c and there held in that adjustment until the bars D are again separated, as before, whereupon it can be lowered 100 into the adjustment, as illustrated in Fig. 3.

When in its folded position, as illustrated in Figs. 1 and 2, the support may be used or employed as a handle with which to carry the frame with its attached article or articles, 105 thereby avoiding the necessity of employing a separate handle in addition to the frame-support.

By reason of the formation of the retaining- 110 plates the support is easily and readily ad-

justed to its lowered position as a support and by slightly springing outwardly the wire rods D may be adjusted to its folded position, where it is held against movement in the recesses c, and when in such position enables the article to be easily and readily carried thereby.

Having fully described my invention, what I claim as new, and desire to secure by Letters Patent, is—

1. An easel-frame comprising a frame, retaining-plates secured to the opposite sides of said frame, each of said plates being formed of a piece of metal, one portion of which is bent at right angles to the other, one portion of the bent plate being provided with a transverse channel, the other portion being provided with a slanting channel, and the bend or angle of the metal being provided with a vertical channel, and a support having bent ends fitting in said transverse channels, the vertical arms of said support being adapted to fit in the other of said channels when raised and lowered, substantially as described.

2. An easel-frame comprising a frame, a bent wire support, and retaining-plates secured to the opposite sides of said frame whereby to engage the ends of said support, each of said plates constructed of a single piece of metal, the two leaves or portions of which are bent at right angles to each other, that portion or leaf which is secured to the frame, being provided with a transverse channel, the opposite leaf being provided with a slanting channel, and the upper portion of the bend or angle between the leaves, being formed into a vertical channel, said channels being adapted to hold said support in its different positions, substantially as described.

Signed at New York, borough of Manhattan, in the county of New York and State of New York, this 31st day of January, A. D. 1906.

SAMUEL BODINGER.
